UNITED STATES PATENT OFFICE.

ESSINGTON N. GILFILLAN, OF CHICAGO, ILLINOIS.

DESIGN FOR A BLANK OR PATTERN FOR STAMPED WASHBOARDS.

SPECIFICATION forming part of Design No. 29,187, dated August 9, 1898.

Application filed March 30, 1898. Serial No. 675,805. Term of patent 7 years.

To all whom it may concern:

Be it known that I, ESSINGTON N. GILFILLAN, a citizen of the United States, residing at Chicago, in the county of Cook and State 5 of Illinois, have invented and produced a certain new and original Design or Useful Shape for a Blank or Pattern for Making Stamped Washboards, of which the following, in connection with the accompanying drawings, is a full, clear, and exact specification.

In the said drawings, Figure 1 is a plan or face view of a pattern or blank embodying my design, and Fig. 2 is a transverse sectional view thereof.

15 The leading features of my design are the body portion A, the projections B, extending from each corner of the body portion A at one end thereof, and the projection C, extending from the opposite end of the body portion A 20 and being of less width than such body portion.

The body portion A is rectangular in general outline, and extending from each of the lower corners thereof is one of the projections 25 B, which is also rectangular. The corners formed by the lower edge of the body portion A and the inner edges of the projections B are slotted outwardly on diagonal lines, as shown at b.

The projection C at the upper end of the 30 body portion A is of substantially rectangular form in general outline; but the corners where the end edges conjoin with the body portion are cut out on curved lines, as shown at c, the cut being made wholly within the 35 projection C and not in the body portion A.

The body portion A is provided with a row of perforations a, extending across it near its upper end, and each side of that part of the body portion located above the line of perforations a is slightly widened, so that the outline of the upper end of the body portion on the sides thereof will diverge outwardly on curved lines gradually merging from the parallel sides of the body portion. 40 45

Having thus described my invention, what I claim as new therein, and desire to secure by Letters Patent, is—

The new and original design or useful shape for a blank or pattern for stamped washboards, substantially as herein shown and described. 50

E. N. GILFILLAN.
